UNITED STATES PATENT OFFICE.

ANNE YOUNG, OF PHILADELPHIA, PENNSYLVANIA.

FOUR-PIECE LADY'S GARMENT.

Application filed July 18, 1927. Serial No. 206,750.

The present invention relates to the art of ladies' wearing apparel, and more especially to a four-piece garment, which comprises the brassière, skirt, step-ins and hose supporters.

It is the purpose of the present invention to provide a garment of such a character as will permit dispensing with corsets or other tight body wearing apparel, enabling the wearer to have perfect freedom of the body, and not in any way strapped in.

Another purpose is to provide improved means for so suspending the hose supporters as to permit the shoulders to withstand the strain, and in attaining this result ribbon straps pass over the shoulders and are stitched to a substantial portion of the brassière and intersecting, in order to keep the ribbon straps from disengaging from the shoulders, and yet hold the hose supporters in firm position, but not so as to cause runs in the hose, or to render the hose too tight.

Another purpose is to suspend the step-ins from the same straps and additionally from other straps or connecting ribbons, which connect the skirt and the brassière spaced from each other at the waist line, thereby giving freedom of movement and also allowing the body to be relatively cool at the waist line.

A further purpose is to provide a brassière, which in its construction, is folded or overlapped on the bias at the front and rear, and substantially so at the rear, which greatly simplifies the construction of the garment, enabling it to withstand wear and at the same time allow a greater number of patterns of the brassière to be cut from a given quantity of material, due to the shape of the blank which forms the brassière.

A still further purpose is to provide a plurality of suspending connecting ribbons between the brassière and the skirt and from certain of which the hose supporters and step-ins are suspended.

It is to be understood that the particulars herein given are in no way limitative, and that while still keeping within the scope of the invention, any desired modification of

details and proportions may be made in the construction of the invention according to circumstances.

The invention comprises further features and combination of parts to be hereinafter set forth, shown in the drawings and 55 claimed.

In the drawings:

Figure 1—is a view showing the four-piece garment as worn upon a figure.

Figure 2—is a view in perspective of the 60 garment removed showing the rear thereof.

Figure 3—is a view similar to Figure 2 but showing the front of the garment.

Figure 4—is a sectional view on line 4—4 of Figure 2.

Figure 5 is a cross-sectional view on line 5—5 of Figure 2.

Figure 6—is a rear view of the brassière showing the skirt and step-ins in dot and dash lines and the hose supporters in full 70 lines.

Figure 7—is a detail perspective view of the step-ins as detached from the garment.

Figure 8—is an enlarged detail sectional view showing how the skirt, the step-ins and 75 the hose supporters are connected to the waist straps, which in turn are connected to the brassière.

Referring to the drawings, 1 designates a brassière, which is made up of four sections 80 of any suitable fabric material. The sections or pieces 4 and 5 at the rear are overlapped on the bias, to not only strengthen the brassière at this point, but also to provide firm suspending means for the shoulder ribbons 6. These shoulder ribbons are stitched to the sections or pieces 4 and 5 and intersect each other a substantial distance over the bias fold of the two sections, where they are additionally stitched, to give 85 strength and durability. The shoulder ribbon 6 after overlying and being stitched to the bias folds of the two sections have their remote opposite terminals merging into and secured to a facing waist band ribbon 7, 90 thereby giving great strength and durability to the brassière.

The sections 2 and 3 in front are also over-

lapped on the bias, but a substantial less distance than the pieces 4 and 5 at the rear, and the shoulder ribbons are also stitched to the sections 2 and 3. Near the waist line of the brassière the sections 2, 3, 4 and 5 are provided with a hem and a facing ribbon as shown at 7. The reason for overlapping the several sections of the brassière at the sides, back and front, is that quite a few 10 of the young ladies, especially those around twenty-seven and over and especially those who have experienced child birth several times, are inclined to be more or less fat and bulged around the waist line, and if the brassière sections were not overlapped on a bias as in the present instance the brassière would rip or break, and therefore would not serve the purpose required. It is the aim to provide a garment of this kind which will 20 allow the body to have freedom of movement without being subjected to undue heat, allowing air to reach the waist line, and due to the bias overlapping of the sections, preventing ripping or tearing of the brassière. 25 The shoulder ribbons in front merge into the hem and facing ribbon, that is stitched between the two at a point where the bias fold of the sections 2 and 3 terminate. However, the shoulder ribbons at the rear also 30 merge into the hem, that is between the hem and the facing ribbon and are stitched thereto, but terminate a substantial distance toward the centre of the bias fold of the sections 4 and 5 of the brassière. The exposed 35 edges of the sections 2, 3, 4 and 5 may be ornamented in any suitable manner, preferably by some appropriate lace edging.

At one side of the brassière as at 8 the adjacent ends of the sections have the usual 40 snap fasteners, so that the brassière may be opened at such point, to permit the garment to be applied to the wearer.

The brassière is connected to the skirt by a plurality of suspending ribbons 9 of 45 double formation. The suspending ribbons 9 also merge into and are connected to the waist band facing ribbons 7 and 11 of the brassière and the skirt. The ribbons 9 merge into a hem and a facing ribbon as at 50 11, and the folded part of the double ribbons constitute tabs or suspending means for step-ins 12, which may be of any approved type, preferably closed in the crotch and open on the sides, as at 13, for the full length 55 of the step-in garment. However, the open side edges of the step-ins at their upper and lower portions at 14 have the snap fasteners, to permit the closing of the step-ins. The step-ins have their various exposed edges 60 ornamented with some suitable lace edging, as at 15. The upper marginal edge of the step-ins have a hem 16 provided with a plurality of fasteners 17 which co-operate with those carried by the tabs, enabling the step-ins 65 to be detached at any time.

Certain of the ribbons 9 are extended in double formation and have connected thereto at their lower ends approved elastic hose supporters 18, the lower ends of which carry the usual hose fasteners 19, which are attached to clamp with the hemmed edge at the tops of the hose, and since the supporters are suspended from the shoulder ribbons, and the waist line of the garment has freedom of movement relative to the body, it is 70 possible for the shoulder ribbons to have sliding movement over the shoulders, to relieve any tension on the hose, in case of any leaning over posture of the body forward or to the rear. 75

Due to the shoulder ribbons intersecting at the rear they are retained relatively permanently with the shoulders, preventing the ribbons from falling off the shoulders, as is the case with many of the garments of the 80 present day.

The invention having been set forth, what is claimed is:

1. A lady's garment consisting of four pieces, the brassière, the skirt, the step-ins, 90 and hose supporters, and shoulder ribbons passing over the shoulders and stitched to the front and back of the brassière, the skirt and the step-ins being spaced at the waist line from the brassière, and ribbons passing 95 across the space between and connecting the skirt and the brassière at points where the shoulder ribbons merge into the waist line of the brassière and assisting in supporting the skirt and step-ins, leaving a space at the 100 waist line allowing the wearer freedom of body and avoiding excessive heat to the body of the wearer.

2. In a lady's garment comprising four garment sections, the combination with a 105 brassière, a skirt, step-ins and hose supporters, the waist line of the skirt and step-ins being spaced from the lower margin of the brassière allowing freedom of the body and avoiding excessive heat to the body of 110 the wearer, of shoulder ribbons to pass over the shoulders of the wearer stitched to the front and the back of the brassière and spanning across the space and connected to the waist line of the brassière and in turn 115 connected to and supporting the skirt and the step-ins, additional ribbons positioned across the space and connecting the brassière and the skirt, the shoulder ribbons at a point beyond and below the space aligning with 120 said hose supporters.

3. In a lady's garment, the combination with a brassière comprising four sections, two in the front and two in the rear, those sections in the front being overlapped on 125 the bias at the front, the sections at the rear being overlapped at the rear, said front and rear sections at opposite sides of the brassière being partially overlapped, a waist band connecting to the lower edges of said 130

brassière sections, of shoulder ribbons to pass over the shoulders, intersecting at and lying across and connected to the two sections of the rear of the brassière and merging into and secured to the waist line of the brassière to retain the overlapped sections in place, said ribbons extending down across the front in substantial parallelism and stitched to the front sections, the opposite ends of the shoulder ribbons merging into 10 and being connected to the waist band of the brassière.

In testimony whereof she affixes her signature hereto.

ANNE YOUNG.
